UNITED STATES PATENT OFFICE

2,461,529

VALVE MECHANISM

John C. Curtis and Elmer G. Gartin, Claremont,
N. H., assignors to Joy Manufacturing Company, a corporation of Pennsylvania

Original application July 1, 1943, Serial No.
493,086. Divided and this application June 22,
1944, Serial No. 541,568

9 Claims. (Cl. 251—91)

1

This invention relates to valve mechanisms and more particularly to improvements in a throttle valve mechanism of a pressure fluid actuated, hammer rock drill.

An object of the present invention is to provide an improved valve mechanism. Another object is to provide an improved throttle valve mechanism for a hammer rock drill of the pressure fluid actuated type for controlling the flow of pressure fluid thereto. A further object is to provide an improved throttle valve mechanism embodying an improved throttle valve and handle construction whereby operation of the valve is facilitated. A still further object is to provide an improved bearing mounting for the throttle valve mechanism whereby the valve operating handle is provided with spaced bearings at the opposite ends thereof. Yet another object is to provide an improved throttle valve mechanism embodying pressure fluid operated means for counterbalancing to a substantial degree the endwise thrust on the valve by subjecting the valve to an opposing thrust. Still another object is to provide an improved connection between the valve and its operating handle permitting free axial movement of the handle relative to the valve while preventing relative rotation therebetween. These and other objects and advantages of the invention will, however, hereinafter more fully appear.

This application is a division of copending application Serial No. 493,086, filed July 1, 1943.

In the accompanying drawing there is shown for purposes of illustration one form which the invention may assume in practice.

In this drawing:

Fig. 1 is a vertical sectional view, with parts in elevation, through a throttle valve mechanism constructed in accordance with an illustrative embodiment of the invention.

Fig. 2 is a view similar to Fig. 1, with certain parts shown in vertical section and others shown in elevation, illustrating structural details of the improved valve mechanism.

Fig. 3 is a horizontal sectional view taken substantially on line 3—3 of Fig. 2.

Figs. 4, 5, 6 and 7 are horizontal sectional views taken respectively on lines 4—4, 5—5, 6—6 and 7—7 of Fig. 1.

In this illustrative embodiment of the invention the improved throttle valve mechanism, generally designated 1, is shown associated with a hammer rock drill generally designated 2, the latter being fully disclosed in copending application Serial No. 493,086. The rock drill includes

2

a pressure fluid actuated hammer motor 3 which is supported and fed by a pressure fluid actuated feeding means 4. Evidently, the improved throttle valve mechanism may be embodied in other types of pressure fluid actuated mechanisms.

The improved throttle valve mechanism 1 is arranged at one side of the hammer motor and feeding means with its axis of rotation disposed in parallelism with the longitudinal axis of the hammer motor and the feeding means. The valve mechanism includes a rotary grasping handle 5 which is preferably of tubular form and is corrugated or longitudinally ribbed at 6 on its exterior to facilitate gripping thereof. The handle is journaled at its ends respectively in a front bracket 7 integral with the cylinder of the hammer motor and upon a rear boss 8 integral with the rear head block 9 of the hammer motor. The front bracket has a bore 10 receiving a bushing 11 in which a reduced stem 12 on the handle 5 is journaled. Axially aligned with the handle is a bore 13 in a valve casing 14 integral with the head block 9, and a rotary throttle valve 15 of cylindric form is arranged in the bore. The throttle valve has a valve stem 16, generally square in cross section, slidably fitted in a square recess 17 in the valve handle 5 so that the valve is connected to the handle for rotation thereby.

Attached at 18 to the rear head block is a conventional hose connection 19 for supplying fluid under pressure to the hollow interior 20 of the throttle valve, and the fluid flowing to the valve acts on the lower end of the valve to force the latter upwardly within the valve receiving bore 13.

To offset to a substantial degree the effect of the pressure of the fluid acting on the lower end of the throttle valve, there is provided a packed piston 21 attached by a screw 22 to the valve 10 and fitting a bore 23 of the valve handle 5 as clearly shown in Figs. 1 and 2. Fluid under pressure may be admitted to the handle bore 23 from the valve interior 20 through an axial passage 24 in the screw 22. Pressure fluid acting on the upper pressure area of the piston 21 tends to force the throttle valve downwardly, in opposition to the upwardly acting pressure on the lower end of the valve, and the pressure of the fluid acting on the upper wall 25 of the handle bore 23 serves

to hold the handle stem 12 upwardly in its bushing 11. To absorb the axial upward thrust of the valve handle 5, there is provided an end-thrust bearing 26 engaging a thrust washer 27 seated against the upper wall 28 of the bracket bore 12 (see Fig. 1). Due to the provision of

the opposing pressures at the opposite ends of the throttle valve, rotation of the valve is made relatively easy.

Now referring to the specific structure of the throttle valve per se, it will be noted that the throttle valve 15 has a port 29 (see Figs. 1 and 4) for connecting the valve interior 20 with a chamber 30 communicating with the inlet passages of the hammer motor 3. The throttle valve has a port 31 (Fig. 5) for connecting the hollow interior 20 of the throttle valve with a circumferentially extending groove 32 on the valve periphery, and this groove is communicable with a feed supply passage 33 leading to the feeding means. The throttle valve has a port 34 communicating with a peripheral groove 35 which is communicable with a passage 36 leading to the lubricator of the drill. Extending longitudinally along the exterior periphery of the throttle valve are shallow lubricant grooves 37 and 38 communicating at the upper ends with an annular groove 39, and lubricant may flow through these grooves to lubricate the walls of the valve receiving bore 13 in an obvious manner. The groove 38 communicates with a peripheral groove 39 which is communicable with the motor in the passage 30. As shown in Fig. 7, rotary movement of the throttle valve 15 is limited by a spring-pressed detent element 40 projecting within a peripheral groove 41 on the valve. A screw plug 42 holds the spring 43 under compression and is removable to obtain access to the parts. This detent element serves to hold the throttle valve in its different position of adjustment.

As a result of this invention an improved throttle valve mechanism is provided having a novel valve and handle construction whereby operation of the valve is facilitated. By the provision of the valve piston in the bore of the throttle valve handle, the pressure acting on the lower end of the throttle valve is opposed, resulting in a smaller net upward longitudinal thrust on the valve, so that the valve may be easily turned and at the same time the valve handle is held upwardly in position against its upper bearing. By the provision of the longitudinally spaced bearings at the opposite ends of the valve handle, the mounting of the valve is improved, and, by the arrangement of the handle longitudinally at one side of the drill, the valve may be readily operated. Other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What we claim as new and desire to secure by Letters Patent is:

1. In a valve mechanism, the combination comprising a control valve, a rotary control handle coaxial therewith, means providing bearings by means of which the opposite ends of said handle are respectively journaled, said bearings permitting limited axial movement of the handle, and pressure fluid operated means for urging said handle axially relative to said valve in the direction toward one of said bearings from the other.

2. In a valve mechanism, the combination comprising means providing spaced bearing portions, a rotary handle extending between said portions

and journaled by means of the bearings thereof, said handle being mounted for limited axial movement and one of said bearings being a thrust bearing and receiving the axial thrust of said handle, a control valve arranged in alignment with said handle and operatively connected thereto, said valve having a pressure area, means for supplying pressure fluid to said valve, the fluid acting on said pressure area of said valve to exert an endwise thrust thereon in one direction, pressure fluid operated means effective upon fluid supply to said valve and associated with said handle for exerting in all positions of the valve an axial thrust on said valve in the opposite direction to reduce the net end-wise thrust on the valve in said one direction, and operative connections between said handle and said valve permitting limited relative axial movement therebetween while preventing relative rotative movement.

3. In a valve mechanism, means providing a pair of spaced projections each having a bearing, a handle extending between said projections and journaled at its ends by means of said bearings, one of said projections having a bore, a rotary throttle valve contained in said bore in alignment with said handle and to which the latter is operatively connected, means for subjecting said valve to the action of pressure fluid to exert an endwise thrust on said valve in one direction, and pressure fluid operated means effective in all positions of the valve and associated with said handle for subjecting said valve to an endwise thrust in the opposite direction to reduce the net endwise thrust on the valve in said one direction.

4. A valve mechanism including a rotary valve having a pressure area at one end thereof, an aligned operating handle therefor, said pressure area at the end of said valve remote from said handle, means for operatively connecting said handle to said valve permitting limited relative axial movement therebetween while preventing relative rotation, bearing means for said valve and handle, means for supplying pressure fluid to said valve at one end thereof, the fluid in said supply acting on said pressure area of said valve for imparting an endwise thrust on said valve toward said handle, and pressure fluid operated means acting between said valve and handle for opposing said endwise thrust, the fluid acting on said last mentioned means concurrently acting on said handle to move the handle axially relative to said valve toward one of said bearing means.

5. A valve mechanism comprising a rotary valve having a pressure area, a handle aligned with said valve for operating the same, means for operatively connecting said valve and handle permitting limited relative axial movement therebetween while preventing relative rotation, bearing means for said valve and handle, a fluid supply, the fluid in said supply acting on said pressure area of said valve for exerting an endwise thrust thereon in a direction toward said handle, and pressure fluid operated means acting between said valve and handle for reducing said endwise thrust by subjecting said valve to a smaller opposing pressure, said opposing pressure concurrently exerting an endwise thrust on said handle in the opposite direction toward a bearing means.

6. A valve mechanism including a rotary valve, a handle for said valve arranged in axial alignment therewith and supported independently of said valve, means for supplying pressure fluid to said valve, means subjected to the pressure of the fluid in said supply means for exerting an axial thrust on said valve in a direction toward

said handle, and pressure fluid operated means effective upon fluid supply to said valve for reducing said endwise thrust by subjecting said valve to a smaller opposing pressure, said pressure fluid operated means being associated with said valve and handle and the fluid exerting such counter-balancing pressure on said valve concurrently exerting an axial thrust on said handle in a direction away from said valve.

7. A rotary throttle valve mechanism including a throttle valve, fluid supply means controlled by said valve, the fluid flowing to said valve acting on one end thereof, and fluid operated means for opposing the pressure produced by the action of fluid on said one end and effective in all positions of said valve and including a piston secured to said valve against relative axial movement and subjected to fluid pressure and acting on the opposite end of said valve.

8. A rotary throttle valve mechanism including a valve and an operating handle for said valve, said handle having a bore, fluid supply means controlled by said valve, the fluid flowing to said valve acting on one end thereof, and fluid operated means for opposing the pressure produced by the action of fluid on said one end and including a piston contained in said handle bore and subjected to fluid pressure and acting on the opposite end of said valve, said piston and handle being mounted for relative axial movement.

9. In a valve mechanism, the combination comprising a control valve, a rotary control handle aligned with and operatively connected to said valve for operating the latter, supporting means

providing bearings by means of which the opposite ends of said handle are respectively journaled, means for supplying pressure fluid to said valve, said valve having an effective pressure area on which the fluid in said supply means acts for exerting an axial thrust on said valve in one direction, and pressure fluid operated means effective upon fluid supply to the valve and associated with said handle for opposing the axial thrust on the valve, the effective pressure area on which the fluid acts in said one direction being somewhat greater than the opposing pressure area so that the valve is held in one axial position against one of said bearings and said handle having an effective pressure area on which the fluid acts whereby the handle is concurrently urged in the same direction against another of said bearings.
